ELECTRONIC STOP CONTROL FOR MOTOR-DRIVEN SWITCHES HAVING TWO-DRIVE MAGNETS

Hans Panzerbieter, Berlin-Siemensstadt, Germany, assignor to Siemens & Halske Aktiengesellschaft, Munich, Germany, a corporation of Germany

Application May 14, 1952, Serial No. 287,788

Claims priority, application Germany
June 19, 1951

2 Claims. (Cl. 179—18)

1

This invention relates to switches used in signalling systems, e. g., automatic telephone systems, and is particularly concerned with an electronic stop control for motor-driven switches having two drive magnets. The invention may be considered an improvement on the disclosure in copending application Ser. No. 281,626, filed April 10, 1952.

The two drive magnets of such a switch become alternately operative under the control of contacts governed mechanically by cams carried by the switch shaft so as to effect the drive by the alternate actuation of the magnets. Control means are provided for stopping such a switch by simultaneously actuating the two drive magnets at the instant when the switch wipers reach desired bank contacts. A switch of this type is disclosed in the German Patent No. 805,286, dated May 15, 1951, and motors of the type referred to are disclosed in copending application Ser. No. 259,076, filed November 30, 1951, now Patent No. 2,654,846 dated October 6, 1953 and also U. S. Patent No. 2,002,546.

One of the two drive magnets is, in a switch of this type, energized in a circuit including an associated closed control contact when its wipers reach engagement with desired bank contacts. The other drive magnet is at this instant inactive but must be energized, because stopping of the switch is effected by the simultaneous energization of both drive magnets. The energization of such other drive magnet is effected by shunting its associated control contact to produce an energizing circuit path for the corresponding drive magnet. The shunting was, prior to the disclosure in copending application Ser. No. 281,626, accomplished by the contact springs of a test relay which energized at the instant when the wipers reached the desired bank contacts. The invention disclosed in this copending application proposes to effect the shunting of the mechanically governed control contact springs (of the drive magnet which happens to be deenergized when the switch should be stopped) over a discharge path in an electron discharge tube which becomes conductive responsive to a potential designating the stopping of the switch. The brake action can thus be initiated during the operation of the switch much faster than by the use of the electromagnetically operating test relay used in the past.

5 The present invention proposes to make the potential which designates the stopping of the switch, effective on the grid of the discharge tube over a transformer. The use of the transformer makes it possible to retain the test and busy potentials usually employed in automatic telephone systems, as distinguished from the prior proposal which connects a stop potential directly to the tube, thereby requiring, in view of the necessary tube control, potentials which differ from the usual test and busy potentials.

10 Details of the invention will be brought out in the description of embodiments shown in the accompanying drawings, wherein

15 Fig. 1 illustrates an embodiment in diagrammatic circuit representation; and

20 Fig. 2 shows a fraction of the circuit of Fig. 1, including a modified transformer.

25 Referring now to Fig. 1, there are two switches indicated by W₁ and W₂. These switches may be of the hunting type having test wipers w_{c1} and w_{c2} which are advanced relative to bank contacts connected with conductors of the trunks or lines to hunt for an idle one of the trunks or lines. The conductors c₁ and c₂ are the test or private conductors of the corresponding trunks or lines. These conductors are in usual fashion multiplied so as to be accessible to a desired number of switches.

30 If it is now assumed that one of the switches, e. g., the switch W₁, has found an idle line having the test conductor c₁, there will result the following circuit: from negative battery (—60 v.) over resistor W₁, winding of relay C₁, conductor c₁, wiper w_{c1} standing on the bank contact 1, contact spring 2p₁, winding II of the relay P₁ designated as P₁II, to ground. A busy potential of —5 volts is now connected over the multiple 35 connected to the bank contacts 1 of all switches having access to the seized line c₁, including the bank contact 1 of the switch W₂ which is accessible to the wiper w_{c2}.

40 It may now be assumed that the switch W₂ is seized. Such seizure causes actuation of the relay V₂ in any desired manner known in the art. The operation of the switch W₂ is under the control of two drive magnets diagrammatically indicated at M₁ and M₂. As has been mentioned before, the drive magnets are governed by contacts (m₁ and m₂) which are mechanically controlled, e. g., by cam means, in such a manner

2

that contact m_1 connects the drive magnet M_1 in an energizing circuit to cause rotation of an armature carried on the switch shaft until such a time when the switch shaft is angularly displaced to a point at which contact m_2 is closed to energize the drive magnet M_2 , while the contact m_1 is opened to disconnect magnet M_1 . The rotation of the armature and switch shaft then continues under the control of the magnet M_2 until an angular switch shaft position is reached in which the contact m_2 is opened to disconnect magnet M_2 , while the contact m_1 is closed to cause re-operation of magnet M_1 .

An idle line may be found, e. g., the line c_2 , extending from the bank contact 2, while the drive magnet M_2 is operative over a circuit including its closed associated control contact m_2 . The switch must now be stopped by shunting the open contact m_1 so as to energize the magnet M_1 , since both magnets must be energized to effect the stopping.

The required shunting of the contact m_1 is effected over the discharge path of the tube R_1 at the instant when the tube becomes conductive by connecting a certain potential to its control grid. This potential is connected at the instant when the switch wipers reach bank contacts from which extend the conductors of an idle line. The wiper w_{c_3} (the remaining wipers have been omitted to avoid encumbering the drawing) first establishes connection with the bank contact 1 which carries a busy potential of -5 volts, as mentioned before. The transformer T_r (Fig. 1) having the primary winding pr connected with the wiper w_{c_3} , while its secondary winding se is connected with the discharge tube R_1 , does not at this instant deliver an impulse for the grid of the tube R_1 which is sufficient to make the tube conductive. The switch therefore continues to rotate. When the wiper w_{c_3} reaches the bank contact 2, the line c_2 extending therefrom being assumed to be idle, there will result a circuit for the primary winding of the transformer T_r from -60 v., resistor W_{12} , relay C_2 , test conductor c_2 , wiper w_{c_3} on bank contact 2, contact $4p_2$, primary winding pr to -5 volts. The secondary winding Se now delivers an impulse to the grid of the tube R_1 , making the tube conductive to provide a circuit path as a shunt for the contact m_1 , thus causing the magnet M_1 to operate and maintaining the operation of the magnet M_2 . The switch stops with its wipers in engagement with the seized line.

The winding I of the relay P_2 , designated as P_2I , is energized in the tube circuit to operate its contact $3p_2$, which short-circuits the tube while completing a holding circuit for both drive magnets. The relay P_2 also closes its contact $2p_2$, to complete the busy circuit for the test conductor c_3 from ground over its winding II, which is designated as P_2II . Accordingly, there is now a busy potential of -5 volts on the test conductor c_2 . The closure of contact $4p_2$ of the relay P_2 causes deenergization of the relay V_2 which was energized before, at the time when the switch was seized in known manner, which does not form part of the invention. Relay V_2 , upon deenergizing, opens its contact $5v_2$ to cause release of the magnets M_1 and M_2 .

It will be appreciated that the use of the transformer permits production of a grid potential for making the tube R_1 conductive independent of the particular potential employed for testing and signalling systems of the type discussed.

The transformer T_r shown in Fig. 1 may be re-

placed by an auto-transformer of the type shown in Fig. 2 at T_{r0} . All other circuit elements remain as shown in Fig. 1. The operation of a circuit employing the auto-transformer T_{r0} conforms to that described with reference to Fig. 1.

I claim:

1. In a switch for use in a signalling system of the class described having a plurality of wipers and a drive motor for moving said wipers comprising two drive magnets and associated control contacts for causing said drive magnets to operate alternately so as to advance said wipers with respect to bank contacts, one of said drive magnets and associated control contact being during the actuation of said switch always operated while the other drive magnet and associated control contact are ineffective, and having stop control means including a discharge tube which becomes operative by a potential applied thereto at the instant when said switch wipers are in engagement with desired bank contacts to energize the ineffective drive magnet so as to cause operation of such drive magnet while the other drive magnet is operated, to thereby effect stopping of said switch by the coaction of the simultaneously operated drive magnets; a device for controlling the operation of said discharge tube, said device comprising a transformer having a secondary winding connected with electrodes of said discharge tube, circuit means including the primary winding of said transformer and a switch wiper for connecting a potential to said primary winding when said switch wiper engages a desired associated bank contact so as to cause current to flow in said secondary winding which is adapted to make said discharge tube conductive, and control circuit means governed by said tube for energizing the ineffective drive magnet independent of the control contact associated therewith.

2. In a switch for use in a signalling system of the class described having a plurality of wipers and a drive motor for moving said wipers comprising two drive magnets and associated control contacts for causing said drive magnets to operate alternately so as to advance said wipers with respect to bank contacts, one of said drive magnets and associated control contact being during the actuation of said switch always operated while the other drive magnet and associated control contact are ineffective, and having stop control means including a discharge tube which becomes operative by a potential applied thereto at the instant when said switch wipers are in engagement with bank contacts associated with conductors of a desired line to energize the ineffective drive magnet so as to cause operation of such drive magnet while the other drive magnet is operated, to thereby effect stopping of said switch by the coaction of the simultaneously operated drive magnets; a device for controlling the operation of said discharge tube, said device comprising a transformer having a primary winding connected in circuit with a test wiper coating with bank contacts from which extend the test conductors of lines accessible to said switch, circuit means extending from the secondary winding of said transformer to electrodes of said discharge tube, the idle potential on a test conductor connected with a bank contact engaged by said test wiper causing said transformer to produce in its secondary winding an operating impulse for said discharge tube to make said tube conductive, control circuit means governed by said tube for energizing the ineffective drive magnet inde-

pendent of the control contact associated therewith while the other drive magnet is energized so as to stop the switch with its wipers in engagement with bank contacts connected with the conductors of a desired line, a relay included in said control circuit and operative with said ineffective drive magnet, and contact means actuated by said relay for short-circuiting said tube and for connecting busy potential to the test con-

ductor of the desired line engaged by said test wiper.
